UNITED STATES PATENT OFFICE.

PAUL A. MEEHAN, OF CLEVELAND, OHIO, ASSIGNOR TO AMERICAN DRESSLER TUNNEL KILNS, INC., OF CLEVELAND, OHIO, A CORPORATION OF NEW YORK.

KILN CAR.

Application filed May 20, 1922, Serial No. 562,497. Renewed February 5, 1927.

The general object of my present invention is to improve the construction of kiln cars such as are employed in moving material to be subjected to heat treatment 5 through a continuous tunnel kiln. A more specific object of my invention is to provide a car construction especially adapted for use in cars larger than ordinary kiln cars and capable of carrying very heavy loads 10 under the extreme thermal conditions experienced in annealing metal plates and the like.

The various features of novelty which characterize my invention are pointed out 15 with particularity in the claims annexed to and forming a part of this specification. For a better understanding of the invention, its advantages and specific objects attained 20 with it, reference should be had to the accompanying drawings and descriptive matter in which I have illustrated a preferred embodiment of my invention.

Of the drawings:

Fig. 1 is a side elevation of an annealing 25 kiln car;

Fig. 2 is a transverse section on the line 2—2 of Fig. 1; and

Fig. 3 is a plan view of the metallic cover for the refractory body of the car.

In carrying out my invention I ordinarily 30 form each car of one or more units, each of which comprises a metallic body or frame A, mounted on track engaging wheels B. Mounted on the metallic frame work A of 35 each car unit is a refractory body formed advantageously, as shown, of a few massive blocks C of earthenware, which are shaped to provide ribs C' and C'' at the opposite ends of the car unit. These ribs are located 40 at different levels so that the ribs on adjacent ends of adjacent cars or car units overlap and thus restrict vertical flow of the kiln atmosphere through the space between the cars or car units between the levels 45 above and below the overlapping ribs. In so far as above described, each truck unit may be similar in construction to the kiln cars ordinarily used in tunnel kilns. To permit of the units being coupled together 50 to form a single car comprising a plurality of units, flanges A' are formed at each end of each unit, and coupling bolts fasten together the adjacent flanges A' of the adjacent units of the car.

Mounted on top of the refractory body

of each unit is a cast metal truck cover D. This truck cover substantially covers the refractory body of the unit and is preferably divided longitudinally into two sections which are similar to one another except that one is provided with a lower extension D' of reduced thickness which is overlapped by an upper extension D'' of the other section. Each cover plate section is formed on its upper side with a rib D''' extending longitudinally of the car adjacent the outside edge of the section and a trough shaped channel D'''' with inclined sides is formed in the upper side of each rib D'''. As shown the ends of the channels are closed by the webs D'' and stiffening webs D'''' extend from the ribs to the adjacent plate-like portions of the cover sections.

A plurality of cast iron or steel balls are mounted in each of the channels D''''. As shown there are three balls E in each channel D''''. These balls form the supports for the cast metal tray or work support F which extends over the top of the composite car, and is formed at its under side with channels F' adjacent each side edge in which the tops of the two rows of balls E are received. The tray F, as shown, is formed with a marginal rim F'' and with lugs F''' at its sides for engagement by a hoisting device for lifting it and its load on to and off the car. The metal plates or other material to be annealed are piled up on the tray F and are ordinarily covered by a removable metallic cover G, which, as shown, is formed of heavy metal plates and stiffening members riveted together, and is in the form of a box with a closed top and open bottom. Hooks G' are provided, as shown, on the sides of the cover to permit its engagement by a suitable hoisting mechanism for lowering it on to and lifting it off the tray F. In the ordinary use of my invention the tray F with its load may be lifted bodily off the car at the end of the annealing or other heating operation, and may then be put back on the car with a truck load of material to be annealed or otherwise heat treated preparatory to a subsequent annealing or other heat treating operation.

With the described construction I obtain the durability and mechanical strength necessary to resist the severe operating conditions to which the apparatus is subjected,

and also obtain a certain flexibility, facilitating the maintenance of the proper load distribution and the avoidance of distortion and fracture from thermal expansion and contraction. The strength required, and the severity of the operating conditions to which the apparatus is subjected may be judged from the facts that in practice a single composite car of three units, with its load may well weigh as much as 60 tons, and the truck cover members D, balls E and tray F may be subjected to temperatures as high as 1700° F. for hours at a time.

Clearance spaces D⁷ are provided at the ends of the channels D⁴ to facilitate planing the wall engaging sides of the channels if and when this is desired. It is one of the advantages of my invention, however, that neither the ball engaging surfaces of the channels D⁴ and F' nor the balls E need be machined, and the balls need not be and in fact preferably are not true spheres nor all of exactly the same size. Indeed, if the ball engaging surfaces of the channels D⁴ and F' were initially made true plane surfaces and the balls were all true spheres of the same diameter, the distortion of the parts and particularly the warping of the tray F resulting from the temperatures to which they are subjected in use would make it practically impossible to properly distribute the load carried by the different balls. With the roughness and inequalities in some or all of the contacting surfaces, incidental to the fact that they are unfinished surfaces of cast metal parts, it is possible to manipulate the balls E either by rotating them about their centers or along the channels D⁴ and F' so that the upper surface of each ball will engage the sides of the corresponding channels F' and thus take its fair share of the load. In effect the balls E form pedestals and the truck cover members D form bases for the pedestals of such breadth and stiffness that a careful spacing of the various balls E is not necessary to insure the avoidance of a localized crushing pressure at any particular point on the top of the refractory car bodies.

In practice some of the balls E should be located at the opposite ends of grooves D⁴ in engagement with the end webs D⁵ thereof as are the end balls E of the middle car unit shown in Fig. 1, to thereby make it impossible for the whole system of tray supporting balls E to roll bodily along the grooves D', and thus shift the tray F longitudinally of the car. By employing balls of suitable diameter, say 6 inches or so the tray F is spaced away from the truck cover members D far enough to provide sufficient space for the manipulation of the balls by the hands of the operator, and also to permit of a circulation of the kiln atmosphere

through the space between the truck cover members D and the underside of the tray. The division of the truck cover into at least two sections D for each car unit minimizes the effect of distortion and reduces the liability of fracture as a result of the thermal expansion and contraction of the parts.

While in accordance with the provisions of the statutes, I have illustrated and described the best forms of my invention now known to me, it will be apparent to those skilled in the art that many changes in form may be made without departing from the spirit of my invention, and that certain features of my invention may sometimes be employed to advantage without a corresponding use of other features.

Having now described my invention, what I claim as new and desire to secure by Letters Patent, is:

1. In a kiln car, the combination with a car body of a metallic work supporting platform, and a plurality of metallic pedestal members resting on said car body and supporting said platform with some at least of the contacting surfaces of said members, car body and platform non-uniform so that by adjustment of said members relative to said car body and platform the weight of said platform and its load may be properly distributed among the various members.

2. In a kiln car, the combination with a car body having a metallic top portion, of a metallic platform and a plurality of metallic members resting on said top portion and supporting said platform with some, at least, of the contacting surfaces of said members, platform, and top portion unfinished cast metal surfaces.

3. In a kiln car, the combination with a car body formed with a cast metal top part provided with grooves in its upper surface running longitudinally of the car, a cast metallic work supporting platform provided with channels in its underside registering with said grooves and cast metal balls seated in said grooves and entering said channels, some of the contacting surfaces of the balls, grooves, and channels being unfinished cast metal surfaces.

4. In a kiln car, the combination with a car body formed with a cast metal top part provided with grooves in its upper surface running longitudinally of the car, a cast metallic work supporting platform provided with channels in its underside registering with said grooves and cast metal balls seated in said grooves and entering said channels, some of the contacting surfaces of the balls, grooves and channels being unfinished cast metal surfaces, and means preventing the balls from rolling along said grooves.

5. In a kiln car, the combination with a

- car body formed with a sectional metallic top part provided with grooves in its upper surface running longitudinally of the car, a metallic work supporting platform provided with channels in its underside registering with said grooves and metal balls seated in said grooves and entering said channels, said balls being of non-uniform spherical shape.
- 10 6. In a kiln car comprising a metallic underframe and a refractory body thereon, the improvement which consists in a metallic cover for said body, a metallic work supporting platform and a series of metallic pedestals supported by said cover and sup-
- porting said tray and spacing the latter away from said cover.
7. In a kiln car comprising a metallic underframe and a refractory body mounted thereon, the improvement which consists in a work supporting platform and means for supporting it from said body above the latter comprising metallic pedestals and a sectional metallic cover for the top of said refractory body forming a base for said pedestals.

Signed at Cleveland in the county of Cuyahoga, and State of Ohio this seventeenth day of May, A. D. 1922.

PAUL A. MEEHAN.
